ALEXIS PRESTON STEELE, OF STATESVILLE, NORTH CAROLINA.

BRICK OR BLOCK CUTTER.

Application filed September 17, 1924. Serial No. 738,273.

To all whom it may concern:

Be it known that I, ALEXIS P. STEELE, a citizen of the United States of America, and a resident of Statesville, in the county of 5 Iredell and State of North Carolina, have invented a new and Improved Brick or Block Cutter, of which the following is a description.

My invention relates to what is generally 10 termed a block cutter and particularly relates to a machine for the indicated purpose for cutting bricks from a solid bar of clay and cutting the bricks to any desired thickness.

15 The known form of machine to which my invention particularly relates embodies a reel lengthwise of which extend angle bars disposed about the axis of the reel, and in practice usually four of such angle bars are 20 employed. The angle bars are equipped with springs and to said springs the outer ends of piano wires are attached, the inner ends of the wires being attached to a ring turning about the shaft of the reel. The 25 angle bars referred to may have twenty wires, more or less, attached thereto for cutting a large number of bricks simultaneously from the bar of clay. The springs referred to are bowed springs and in order 30 to facilitate the attachment of a wire to a spring, the spring is stressed and flexed in a direction toward the axis of the reel and the flexed end of the spring has movement 35 in a slot in the angle bar, the spring being pressed toward the inner end of the slot for the convenient engagement of the loop of the wire with an end of the spring. In practice it is found that the clearance permitted 40 the spring in the slot of the angle bar in flexing the same for the attachment of the wire allows an excessive space in subsequent operations and proves objectionable in important particulars. For example, when the 45 wires cut through hard or rough ground clay or shale, the wires are flexed to a material extent and thereby flex the spring to a proportionate degree as regards the movement of the spring in the angle bar. The consequence is that near the finish of the 50 cut the wire jumps through the clay bar and the reaction of the spring occurs with a snap. The result is that breakage of the wires not infrequently occurs. Furthermore,

upon the breaking of a wire the sudden liberation of the spring causes it to rebound to the full extent of the clearance permitted the spring in the slot of the angle bar so that the liberated spring strikes the angle bar at the end of the slot with great force, thus causing breakage of the end of the 60 spring.

The prime object of my invention is to minimize or eliminate the breakage of the wires and the breakage of the springs in the reel upon the rebound of the springs 65 as referred to.

The above object is attained by providing means of a character to permit the complete flexure of the spring in stressing to facilitate the connection of a wire therewith but 70 which means will function to limit the rebound of the spring.

The nature of my invention and its distinguishing features and advantages will clearly appear as the description proceeds. 75

Reference is to be had to the accompanying drawings forming a part of this specification, it being understood that the drawings are merely illustrative of one example of the invention.

Figure 1 is a transverse vertical section largely diagrammatic showing the main features of the reel with its angle bars and spring, the springs being equipped with devices embodying my invention and shown in 85 side elevation;

Figure 2 is an elevation on an enlarged scale of one of the springs and a fragment of the angle bar to which the spring is secured;

Figure 3 is a section on the line 3—3 of Figure 2;

Figure 4 is a view showing the angle bar in cross section and a spring in elevation, together with a tool usually employed to 95 stress the spring and flex the same for the attachment of the wire.

In the illustrated example of my invention, the numeral 10 designates the usual reel of the machine to which the invention 100 relates, said reel turning about a shaft 11. The numeral 12 indicates the ring on the shaft formed with arms 13 beneath which the piano wires 24 pass to be secured to the ring at points thereabout as at 15. The 105 outer ends of the springs are attached to

bowed springs 16 secured at one end to the angle bars 17 by bolts 18. The numeral 19 indicates the usual slots in the other flange of the angle bar through which one 5 end of each spring 16 passes, said end of each spring being secured to the outer end of a wire 14, the wire at the outer end being in looped form and the end of the spring receiving the wire having a lug 20 and a 10 notch 21, whereby the loop of the wire is securely engaged with the spring.

In accordance with my invention I provide on the spring 16 a block 22 which is free to move in a slot 23 in that end of the 15 spring 16 to which the wire is to be attached. A bolt 24 is screwed into the block 22 and a flange 25 thereon bridges the block 22 to retain the block in position while permitting longitudinal movement thereof 20 in said slot.

The blocks 22 will thus be carried about the axis of the reel 10 with the turning of said reel, there being a plurality of the angle bars 17, usually four in number, having 25 each its equipment of springs 16 and the blocks are free to move by their own gravity alternately toward the opposite ends of the slot. At the front of the reel which is the left of Figure 1, the angle bars 17 will bring 30 the springs 16 to a position with the wire attaching arm sufficiently near the vertical for the blocks 22 on the springs to gravitate to what is then the lower ends of the slots 23. Thus, the blocks 22 will be below and away 35 from the slots 19, thereby leaving the full clearance of the slots 19 for the flexure of the spring arm for the attaching of a wire 14, after securing the inner end of the wire at 15 to ring 12. As the reel continues to 40 revolve and passes over the top to the opposite side or right-hand side of the reel, shown in Figure 1, it will be seen that the block 22 shown in connection with the spring 16 has now dropped toward the free end of 45 the spring, that is to say, to the outer end of the slot 23. At this time, the block 22 extends through or at least into the slot 19. Consequently, it will be seen that if the wire 14 shown at the right of Figure 1 which is 50 approaching the bar A of clay, disposed within the reel 10 on a bed C should find undue resistance, owing to the ingredients or density of the bar A, the flexure of the wire 14 under the resistance is limited because the block 22 limits the movement of 55 the flexed spring arm in the slot 19. The consequence is that upon the rebound of the spring after the wire 14 cuts through the bar A the spring will have but a limited clearance for reaction and it will therefore minimize or wholly prevent the rebound of the spring from snapping the wire 14 or breaking the spring by undue impact against the angle bar 17 at the outer end of slot 19. 60 Following the passing of a wire 14 through 65

the clay bar A, the spring will pass again to a position (as at the left of Figure 1) where the block 22 will gravitate to a position below the slot 19 so that any wire may be readily attached to the spring, by leaving 70 the spring free to flex to the full extent of the slot 19.

The numeral 26 indicates the friction rollers which center and support the reel 10, said rollers being on a fixed spider 27 rigid 75 with the shaft.

The letter B indicates a bowed tool to be applied to the machine at the spring 16, said device having a lever b to compress the spring 16 for the connecting of the cutting 80 wire 14.

I would state in conclusion that while the illustrated example constitutes a practical embodiment of my invention, I do not limit myself strictly to the exact details herein 85 illustrated, since, manifestly, the same can be considerably varied without departure from the spirit of the invention as defined in the appended claims.

Having thus described my invention, I 90 claim:

1. In a cutter of the class described employing a reel having cutter wires and bars disposed about the reel and provided with springs for tensioning the cutter wires: a block on that arm of each spring to which a wire is attached, the bars carrying the springs having slots affording clearance for the movement of an arm of each spring, and said blocks each adapted to gravitationally 95 assume a position at a slot of the angle bar or a position away from said slot so that in one position of each block said spring arm may have movement to the full extent of a slot and in another position of the block the 100 movement of the spring in said slot will be limited.

2. A cutter of the class described employing a reel and having springs disposed about the reel and connected with said wires to 110 tension the same, as well as means affording clearance for limited movement of the springs in flexing the same for the attachment of the wires: movably mounted means adapted to be positioned to offer restriction 115 in the flexure of the springs or positioned to afford a less restricted movement of the springs.

3. A cutter of the class described employing a reel and having springs disposed about 120 the reel and connected with said wires to tension the same, as well as means affording clearance for limited movement of the springs in flexing the same for the attachment of the wires: and means to variably 125 permit flexure of the springs following the tensioning of the cutter wires.

4. As an article of manufacture, a spring to tension the cutter wires of brick cutters, said spring adapted at one end to be secured 130

to a support and presenting a free arm, means affording a limited movement of said spring arm, and means carried by said spring and adapted to assume positions permitting a greater or less stressing of the spring.

5. A spring to tension the wires of brick

cutters, said spring adapted at one end to be secured to a support and presenting a free arm at the opposite end, and a block 10 free to gravitationally slide on said spring arm.

ALEXIS PRESTON STEELE.
